Primary Examiner — Wan Laymon*(74) Attorney, Agent, or Firm* — Andrus Intellectual Property Law, LLP(57) **CLAIM**

The ornamental design for a clip for a self-ligating bracket, as shown and described.

DESCRIPTION

FIG. 1 is a perspective view of a clip for a self-ligating bracket;

FIG. 2 is a top view thereof;

FIG. 3 is a front view thereof;

FIG. 4 is a right side view thereof;

FIG. 5 is a left side thereof;

FIG. 6 is a bottom view thereof; and,

FIG. 7 is a back view thereof.
